UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

HEATING APPARATUS.

1,316,861.

Specification Clutterdike Patented Sept. 23, 1919.

Application filed December 11, 1915. Serial No. 66,269.

to all whom it may concern:

Be it known that I, HENRY W. O'Dowd, a citizen of the United States, and a resident of Jersey City, county of Hudson, 5 and State of New Jersey, have made certain new and useful Improvements in Heating Apparatus, of which the following is a specification.

The present invention relates to improvements in stoves of a certain type, disclosed by me in two prior patent applications, respectively filed on May 13, 1915 and October 16, 1915, Serial Nos. 27,761 and 56,189.

In the applications aforesaid are shown 15 two forms of gas-stoves, provided each with upper and lower heat-generating chambers, situated one above and the other below an intermediate oven. The surplus flow of calorific from the upper chamber, in each 20 stove, is rendered available for heating the oven, with or without the aid of the heat currents from the lower chamber. To this end, the currents and volatile results of combustion originating in the upper chamber 25 are arranged to pass out therefrom not only in a straight course, in a plane higher than that of the oven as usual, but also along a sinuous path leading around the latter into an additional discharge flue located at the rear. On the other hand, the 30 currents and products of combustion arising from the lower chamber are first led into the oven, and thence conveyed to the same discharge flue. The operation of these 35 stoves, therefore, involves a dual method of heating, which is both direct and semi-direct, as related to the oven. The method is direct as regards the utilization of the heat generated in the lower chamber, and 40 semi-direct, at least for part of the heat applied, in so far as the upper generating chamber is concerned. As disclosed in the said patent applications, and likewise shown herein, the heat from the lower generating chamber passes up into the interior 45 of the oven, either through the bottom or the sides thereof, and the cognate products of combustion, escaping through apertures in the oven top, are carried off into the flue 50 at the back of the stove. At the same time, the heat from the upper generating chamber intended for heating the oven is brought down through a circuitous channel or a plurality of channels coursing mostly

about the exterior of the oven body, and the 55 accompanying products of combustion are caused to mingle with those from the lower chamber while following the way out into the common discharge.

Among the several features that distinguish the present invention from its said prototypes is the inclusion therein of a priming device, the object of which is to promote, accelerate, and maintain the draft from the upper heat-generating chamber of the stove through the indirect egress afforded by the channel or channels circuiting around the oven and terminating in its external outlet. This device is rendered 60 permanently operative by keeping the direct egress out of the upper chamber constantly open within certain restricted limits, so that it is no longer required, as formerly, to open the door of the oven and operate a damper in the back flue for the 65 purpose of allowing heat to pass out into the latter from the upper chamber, thereby unbalancing the weight of the air sufficiently to relieve the pressure thereof on the indirect egress and eventually enabling the 70 heat to flow downward through the same and around the oven.

Another salient feature, characteristic of the invention, resides in the transposition of the damper for the discharge flue from 75 its accustomed place at the back to a point well forward of the oven,—a change which secures the twofold advantage of maintaining a protracted contact of the heat currents from the lower generating chamber 80 with the oven top, and of permitting a novel control of the damper and oven door that precludes interference with the draft established for the upper generating chamber, by leaving both its direct and indirect 85 egresses unobstructed at all times.

Other features, of greater or less importance, together with their respective objects and advantages, will be best understood and appreciated by reference to the 90 following detailed description and the drawings hereto appended.

In the said drawings:

Figure 1 is a side sectional elevation of 95 a stove or range wherein the said improvements are embodied, the section being on the irregular line 1—1 of Fig. 2, looking toward the left;

Fig. 2 is a vertical section on the irregular line 2—2 of Fig. 1, looking to the right;

Fig. 3 is a sectional plan showing the upper part of the stove, the cooking top thereof being removed, and the section made on the irregular line 3—3 of Fig. 1, looking downward; and

Fig. 4 is a fragmentary view, on an enlarged scale, of the damper and its oven door connection.

The body of the stove may be of any desired shape and construction that will afford a staunch structure capable of retaining heat within the interior thereof, such for example as was shown in either of the said patent applications. For the purposes of this specification, it is sufficient to give a simple outline of the stove body, and therefore the drawings hereto annexed represent it as consisting merely of a plain quadrangular casing, as 11, rising from a correspondingly shaped base 12, and having a flanged upper border 13, surrounding a removable cooking top or surface 14, with reducing rings 15, and lid 16. Interiorly, the casing 11 may be lined with asbestos sheets, as 17, or otherwise insulated in any approved manner.

In the center of the said casing, preferably, is placed the oven proper, consisting of a rectangular recipient having side plates 21, 22, top and bottom plates 23, 24, and a back plate 25, all of which are rigidly joined together and supported from the surrounding walls of the casing. This oven may be of any convenient size or capacity, and, if pertaining to a hotel range, will usually be furnished with a plurality of removable shelves, (not shown), adapted to slide on and off opposite side rests, as 26, 27. A door 28, preferably of the drop type, spring cushioned and self-leveling, closes the oven in front, in the same manner as was described in the aforementioned patent applications.

Above the said oven is a heat chamber 31, which occupies nearly the entire space inside the upper portion of the casing 11 and is covered up by the flanged border and cooking top previously described. Within this chamber may be located any suitable means designed to generate, develop, supply or receive the amount of heat units necessary for the operation of the upper part of the stove. As the form of stove herein illustrated, like the preceding forms, is well adapted for the economical use of gas as a fuel, the said chamber 31 has been represented in the drawings as fitted with a cluster of annular, concentric burners 32, which are respectively connected to a main supply-pipe 33, by separate feed-pipes 34, equipped each with an air-mixer, as 35, and a valve, as 36, provided at or near their juncture with the said supply-pipe. The cluster of burners is shown resting on a seat 37, slidable centrally upon a plate 38, that extends horizontally

lengthwise from the front to the rear of the casing 11, just above the oven door 28, but laterally stops short of the sides of the casing, at points coincident with the vertical planes of the oven's side plates 21, 22, or 70 prolongations thereof. A layer of firebrick 39, or similar, refractory material, is placed upon the plate 38 so as to surround the cluster 32 thereon, except at the middle front portion where the feed-pipes enter and lead 75 from the supply-pipe to the several burners. It is understood that these burners can be lit singly, or conjointly, in divers combinations, or all collectively, to produce the heat required for cooking on the stove's surface, 80 and that the latter is made removable to permit immediate exposure of the cooking utensils to the flames. Meanwhile the invention contemplates utilizing also the same fire for heating the oven thereunder, as will now be 85 described.

A direct egress out of the chamber 31 is first afforded to the volatile products of combustion, through an exit 41 in the back plate of the casing 11, and into a discharge compartment 42, communicating therewith under the flanged border 13 at the rear of the stove. From the compartment 42 the products of combustion pass up through one or more slots or jet openings, as 43, formed 90 within a flanged aperture 44 in the rear border 13, to the flange of which aperture is fitted an outlet-pipe 45. The latter may lead at once into the atmosphere or be connected to a chimney, as preferred. The outward flow of the products of combustion is restricted or delayed, as will be seen, by the slot or slots 43, which in the embodiment of the invention shown in the accompanying drawings are produced by placing inside the 95 flanged aperture 46 a funnel-shaped duct or spout 46, more particularly referred to hereinafter.

Besides the direct egress above spoken of, the upper chamber 31 has an indirect egress for the heat currents and combustion products therein, the same comprising vertical channels 49, 50, leading downwardly from the chamber one by each side of the oven; a horizontal channel 51 interconnecting the 110 said vertical channels and extending under the oven therebetween; a vertical flue 52 in communication with this horizontal channel, at the rear of the stove; and an opening 53 discharging from the said flue into the aforesaid spout 46. As already stated, the spout 46 is placed within the flanged aperture 44, hereinbefore mentioned as fitted with the outlet-pipe 45. The channels 49, 50 and 51 are formed by partitions 54, 55 and 56, preferably consisting of metal sheets supported from the walls of the casing 11 and held in parallelism with the adjacent sides and bottom of the oven, respectively. The flue 52 occupies a space left between the rear plate 115

25 of the oven and the back of the outer casing. The opening 53 is made in the back of the casing, at the upper end of the flue.

It will be observed that both egresses, direct and indirect, for the heat currents and volatile products of combustion emitted from the upper chamber 31 are open and have a common outlet through the pipe 45, but the outlet is differential in that the slot 10 or jet opening 43 is of less area than the passage offered by the spout 46. The effect of this construction and arrangement is that when the burners 32 are lighted, a small amount of heat passes immediately into the 15 discharge compartment 42, circulates around the spout 46 therein, and slowly escapes to the outlet 45 through the slot 43. The atmospheric column in the outlet is thereby unbalanced and a suction is produced on the 20 underlying spout and flue, as the air in the latter becomes lightened, allowing a pull to be generated forthwith on the channels 49, 50 and 51, and thus drawing very rapidly the heated products from the upper chamber 25 31 down into these channels, thence up the flue 52, and out through the opening 53, spout 46, and pipe 45. Once the indirect course of the heat currents and products of combustion has been established, it is automatically maintained by and in proportion 30 to the flow of caloric from the cluster of burners, assuming that the stove or range is kept properly covered, either with its own lid and rings or with utensils set in their 35 places.

Under the oven is another heat-generating chamber 57. This lower chamber has been shown in the annexed drawings as co-extensive with the entire bottom part of the casing 11, but the dimensions thereof may vary within any desirable limits. As illustrated, the chamber 57 is heated by a set of parallel burners 58, extending from the front of the casing to supports 59, located inside 45 the same at the rear. The set is suitably positioned over a floor plate 60, which may be insulated underneath, as at 61. Each burner in the set has its air-mixer 62, valve 63, and feed-pipe connection 64, with a supply-pipe 50 65. The heat and volatile products of combustion arising from this set of burners first impinge against the underside of the channel 51, previously mentioned, and thence are diverted into flue spaces 66, 67, provided between the side partitions 54, 55, also before 55 mentioned, and the adjacent sides of the casing 11. These flue spaces thus overlap the channels 49 and 50, and they are placed in communication with the interior of the oven 60 by means of tubular flueways 68, 69, traversing the same channels at different levels.

The heat currents and volatile products of combustion rising from the lower chamber 57 into the interior of the oven naturally 65 ascend to the upper part of the latter, and

thence they are made to enter a horizontal passageway 72, located thereabove. Preferably, and as shown, the passageway extends along the middle portion of the oven top 23, from the front of the casing 11 to 70 the oven's back plate 25, and is divided off a vacant space 73, left between the top of the oven and the plate 38 under the refractory material 39, before described. A row of openings, as 74, is provided in the forward part of the top 23 to admit the heat currents and products of combustion into the said passageway, which they follow from the front to the rear, where similar openings 75 are made for their escape into the back flue 75 80 52, through an extension 76 of the said plate 25. The flow from the lower chamber 57 consequently encounters and mingles with the like flow from the upper chamber 31 in the vertical flue 52, from which the combined currents, chiefly volatile products of combustion, pass into the spout 46, by way of the exit 53, and off through the outlet 45.

As the opening of the oven door would tend to retard the suction on the indirect 90 egress for the currents and combustion products from the upper chamber 31, if the openings 74 in the oven top also were left uncovered, a damper 79 is provided for these openings. This damper is arranged to drop 95 down by gravity, so as to close the openings 74 when the oven door is opened; and it rises from the openings upon closing the oven door. As shown in Figs. 1 and 4, the said damper is conveniently oscillated to 100 raise it from the openings, by means of a rod 80, jointed to its outer edge, as at 81, and guided by a staple 82, into contact with the door of the oven, when the latter is being closed. But, from the moment the door 105 is opened, it recedes from the rod 80, and as a consequence the damper swings downward over the openings, thereby closing them and operating to maintain a steady draft, pull, or suction on the aforementioned indirect 110 egress.

In its broader aspect the invention is not limited to the precise details of construction and arrangement of parts herein shown and described, since manifestly the same can be 115 varied in numerous ways without deviating from the fundamental principles of the invention or sacrificing any of its chief advantages.

I claim:

1. A stove including an oven, sources of heat located above and below said oven, flues partly surrounding said oven for conveying heat currents from the lower source into the oven, channels intermediate said flues and oven leading currents from the upper source down around the oven, an outlet for the products of combustion, and a primer in said outlet.

2. A stove including an oven, sources of 130

- heat located above and below said oven, flues partly surrounding said oven for conveying heat currents from the lower source into the oven, channels intermediate said flues and oven leading currents from the upper source down around the oven, an outlet for the products of combustion, and a cut-off controlling the discharge from one of said sources.
- 10 3. A stove including an oven, sources of heat located above and below said oven, flues partly surrounding said oven for conveying heat currents from the lower source into the oven, channels intermediate said flues and 5 oven leading currents from the upper source down around the oven, an outlet for the products of combustion, a primer in said outlet, and a cut-off controlling the discharge from one of said sources.
- 15 4. A stove including an oven apertured at the top and sides, a source of heat above and a source of heat below said oven, flues partly surrounding said oven for conveying currents from the lower source into said 10 oven and from the upper source down around the sides thereof, a flue connecting the openings in the top of the oven and the side flues, and a damper associated with said openings.
- 20 5. A stove including an oven apertured at the top and sides, a source of heat above and a source of heat below said oven, flues partly surrounding said oven for conveying currents from the lower source into said 15 oven and from the upper source down around the sides thereof, a flue connecting the openings in the top of the oven and the side flues, and a damper associated with said openings, a door on said oven, said 20 damper being normally open and operable to close the openings when the oven door is open.
- 25 6. A stove including an oven apertured at the top and sides, a source of heat above and a source of heat below said oven, flues partly surrounding said oven for conveying currents from the lower source into said 30 oven and from the upper source down around the sides thereof, a flue connecting the openings in the top of the oven and the side flues, a damper associated with said 35 openings, an indirect egress for the products of combustion from one of the sources of heat, and a direct egress associated there- 40 with and constituting a primer.
- 35 7. A stove including, in combination, an oven, flues disposed around said oven, a casing surrounding said flues, and in spaced relation thereto, said oven being provided with 45 openings in its sides and top, an upper source of heat, a lower source of heat, means directing heat currents from the lower source of heat outside of said flue spaces and into said oven, a direct and an indirect egress for the products of combustion, and means for di- 50 recting heat currents from the upper source of heat down around the oven and out through the indirect egress.
- 40 8. A stove including, in combination, an oven, flues disposed around said oven, a casing surrounding said flues, and in spaced relation thereto, said oven being provided with 45 openings in its side and top, an upper source of heat, a lower source of heat, means 55 directing heat currents from the lower source of heat outside of said flue spaces and into said oven, a direct and an indirect egress for the products of combustion, means for directing heat currents from the upper source of heat down around the oven and out through the indirect egress, and means for directing heat currents from the lower source of heat over the top of the oven and commingling them with the products from the lower source of heat.
- 45 9. A stove including, in combination, an oven, flues disposed around said oven, a casing surrounding said flues and in spaced relation thereto, said oven being provided with 50 openings in its side and top, an upper source of heat, a lower source of heat, means 55 directing heat currents from the lower source of heat outside of said flue spaces and into said oven, a direct and an indirect egress for the products of combustion, means for directing heat currents from the upper source of heat down around the oven and out through the indirect egress, means for directing heat currents from the lower source of heat over the top of the oven and commingling them with the products from the lower source of heat, and a primer disposed in the indirect egress.
- 50 10. A stove including, in combination, an oven, flues disposed around said oven, a casing surrounding said flues and in spaced relation thereto, said oven being provided with 55 openings in its side and top, an upper source of heat, a lower source of heat, means 60 directing heat currents from the lower source of heat outside of said flue spaces and into said oven, a direct and an indirect egress for the products of combustion, means for directing heat currents from the upper source of heat down around the oven and out through the indirect egress, means for directing heat currents from the lower source of heat over the top of the oven and commingling them with the products from the lower source of heat, a primer disposed in the indirect egress, and means for directing a portion of the heat currents from the upper source of heat around said primer.
- 55 11. A stove comprising an oven provided with 65 openings in its top and sides, flue spaces disposed around the sides and top of said oven, said top and side flues being in communication, an upper source of heat, a lower source of heat, a casing surrounding said oven and said sources of heat and in 70

- spaced relation to said flues, flue members 45
directing heat currents from said lower
source into said oven and out through the
top thereof, a direct and an indirect egress
5 for the products of combustion, means di-
recting the products of combustion from the
upper source of heat down around the oven,
said products commingling at the indirect
egress, and a primer disposed in the indi-
rect egress. 10
12. A stove including an oven with an
apertured top, an overlying flue adapted to
receive heat currents through the aperture
therein, a damper controlling the passage of
15 currents from the oven to said flue, means
operating to open said damper upon the
closing of the oven door, an external outlet,
a heat generating chamber having an in-
direct egress to the latter, and a primer in
20 said outlet serving to promote a draft
through the indirect egress and the flue
upon the opening of said damper. 12
13. A stove including an oven, a heat gen-
erating chamber thereabove, downwardly
25 directed channels conveying currents from
said chamber upon the sides, bottom, and
back of said oven exteriorly, a lower heat
chamber, and upturned flues leading cur-
rents from the latter into the oven on opposite
30 sides thereof transversely of said channels. 13
14. A stove including a heat chamber with
an upper exit, a discharge compartment re-
ceiving part of the currents directly there-
from, a lower channel conveying another
35 part of the currents indirectly from said
chamber to said compartment, a spout to
said channel rising within the compartment
opposite said exit, a second heat chamber,
means for leading currents from said heat
40 chamber into the oven, and a flue conducting
currents from the latter-named chamber into
said spout. 14
15. A stove including an oven with an
apertured top, a heat chamber thereabove,
a channel leading currents from said cham- 45
ber down the sides, under the bottom, and up
the back of said oven exteriorly, means dis-
charging other currents of heat into the inter-
ior of the oven through lateral apertures
50 therein, and an outlet drawing the latter-
named currents through the aperture in said
top and across its surface. 15
16. A stove including an oven with aper-
tures in its sides and top, a chamber below
55 said oven supplying it with heat interiorly
through its said lateral apertures, a flue over-
lying said top in position to receive the cur-
rents passing through the oven from said
chamber, an upper heat chamber, and a chan-
nel conveying currents from the latter upon 60
the sides, bottom, and back of the oven ex-
teriorly. 16
17. A stove including an oven with aper-
tured sides and top, a lower heat chamber,
flues discharging currents from said cham- 65
ber into the interior of said oven through
its sides and thence above the top thereof, an
upper heat chamber, and channels conveying
currents from the latter exteriorly upon the
70 oven within said flues. 17
18. A stove including an oven apertured
at the sides and top for the passage of heat
therethrough, an upper heat chamber, chan-
nels adapted to convey currents from said
chamber around the oven below its said top
75 exteriorly, a lower heat chamber, flues rising
from said lower chamber adjacent to oppo-
site channels, and flueways traversing the
latter so as to discharge currents from said
flues into the oven through its side apertures. 80

In testimony whereof, I have signed my
name to this specification.

HENRY W. O'DOWD.
